UNITED STATES PATENT OFFICE.

JEROD TYLER, OF ST. MARY'S, PENNSYLVANIA.

CAR-HEATER.

SPECIFICATION forming part of Letters Patent No. 374,020, dated November 29, 1887.

Application filed May 6, 1887. Serial No. 237,330. (No model.)

To all whom it may concern:

Be it known that I, JEROD TYLER, of St. Mary's, in the county of Elk and State of Pennsylvania, have invented a new and Improved 5 Car-Heater, of which the following is a full, clear, and exact description.

The object of my invention is to provide a new and improved car-heater which is fire-proof and is thus prevented from setting the 10 car on fire in case of a collision or other accident.

The invention consists in the construction and arrangement of various parts and details and combinations of the same, as will be fully 15 described hereinafter, and then pointed out in the claims.

Reference is to be had to the accompanying drawings, forming a part of this specification, in which similar letters of reference indicate 20 corresponding parts in all the figures.

Figure 1 is a central sectional elevation of my improvement. Fig. 2 is a perspective view, with parts broken out, of part of my improvement. Fig. 3 is a similar view of the lower part 25 of the same. Fig. 4 is a sectional side elevation of the upper part of my improvement, showing several parts in an open position; and Fig. 5 is a cross-section of the same on the line $x-x$ of Fig. 4, showing the valve of the fire-extinguishing device closed.

The heater A of my improvement is of suitable size and material, and provided with the usual interior arrangement of grate-bars B, having a rack, B', on their under sides, and 35 with said rack B' meshes a pinion, B², secured to a rod, B³, extending outward and provided on its outer end with a handle, B⁴, for shaking said grate-bars B. The heater A is also provided with the main door C, adapted to slide 40 in the guides C', and secured in a closed position by a suitable lock, C². The rearward motion of said door C is limited by a stop, C³, thus preventing the door from falling out of the guides C' when the door is opened. Below 45 the main door C is placed the damper-door D, sliding in suitable guides, D', secured to the outside of the heater A, and in the damper-door is formed an aperture, D², registering with an aperture, D³, formed in the 50 shell of the heater A, and opening directly into the latter below said grate-bars B. In the bottom of the heater is formed the ash-

pit E, provided in front with the usual ash-pit door, E', located below the damper-door D.

The heater A is placed in a cylindrical casing, F, made preferably of strong boiler-iron, and is provided with the heavy base F', on which is secured, in any suitable manner, the base of the heater A. The casing F is provided with three horizontal partitions, F², F³, 60 and F⁴, and also with a top plate or cover, F⁵, which cover and partitions are firmly secured by bolts or other suitable means to the shell of the casing F. In the middle of the top plate, F⁵, is hinged a door, F⁶, opening outward, and on the side of the casing F is hinged the main door F⁷, which opens directly upon the front of the heater A, so as to give access to the doors C, D, and E' of the heater A. The partition F² rests on the top plate of the 70 heater A, and said partition supports the fuel-extinguishing device G, provided with the vessel G', having in its bottom a threaded aperture, G², passing through said partition F², and screwing on a threaded projection, A², formed on the top plate of the heater A. Said projection is provided with an aperture, A³, leading to the interior of the heater A.

On the inner end of the outlet G² is formed a seat for the valve G³, provided with the upwardly-extending short stem G⁴, having a slot G⁵, through which passes the pin H', secured to the lower hollow part of the vertical rod H, in which said stem G⁴ is held and adapted to slide vertically. On the upper end of the stem 85 G⁴ presses a spring, H', held in the hollow part of the rod H, so that the valve G³ yields when pressed on its seat in the outlet G².

The vessel G' is provided with an inlet-pipe, G⁶, which extends to the outside of the casing 90 F and carries at its outer end an upwardly-extending cup, G⁷, which serves for filling the vessel G' with a fire-extinguishing fluid of suitable ingredients.

An outlet-pipe, G⁸, is secured to the vessel 95 G', near its bottom, and extends to the outside of the casing F. The pipe G⁸ is provided between the vessel G' and the casing F with a valve, G⁹, connected with and operated by the rod G¹⁰, extending to the outside of the casing F. 100 This pipe G⁸ serves to withdraw from the vessel G' part of the extinguishing-fluid whenever desired. The rod H passes through the top of the vessel G' and through the partition

F^3 , extending a suitable distance above the latter. On this upper part of the rod H is coiled a spring, H^3 , resting with one end on the partition F^3 and with its other end presses 5 against the arm I , secured by one end to the upper end of the rod H and being bent downward to within a short distance of the upper face of the partition F^3 . The arm I extends to one side of the casing F and is guided at its 10 outer end in guides I' , secured to the inside of the shell of the casing F . The arm I is held in its lowermost position by the bolt J , mounted to slide in the keeper J' , fastened to the partition F^3 . One end of the bolt J engages 15 the top of said arm I , and the other end of the bolt J is connected by the link J^2 with the short end of the bell-crank lever J^3 , pivotally mounted in the bearing J^4 , secured to the upper face of the partition F^3 . The outer end 20 of the long arm of the bell-crank lever J^3 is connected with an arm, K' , extending from the lever K , fulcrumed on the bearing K^2 , secured to the top of the partition F^3 .

On the long end of the lever K is secured a 25 rod, K^3 , which extends upward and carries at its upper end a cup, K^4 , passing through an opening formed in the partition F^4 . When the long end of the lever K is in its lowermost position, then the cup K^4 is guided in said 30 opening in the partition F^4 , and the cup supports at its upper end a heavy ball, L , placed so that when the shell F receives a shock from a collision or other accident then the ball L is thrown off of the cup K^4 and rolls upon the 35 partition F^4 . To the other end of the lever K , next to the arm K' , is secured an upwardly-extending pin or rod, K^5 , on which is coiled a spring, K^6 , resting with one end on the outer end of the lever K , and with its other end 40 against the under side of a bracket, K^7 , secured to the inside of the shell F . The bracket K^7 is provided with a slot, K^8 , into which projects the upper end of the rod K^5 , so that when the lever K oscillates on its fulcrum the rod 45 K^5 moves in said slot K^8 .

To the arm I is secured a downwardly-extending rod, N , which passes through suitable slots in the partitions F^2 and F^3 , and is pivotally connected at its lower end with the 50 crank-arm N' , secured to the shaft O , mounted in the standards O' , secured to the base F' of the shell F . The rod N is guided in and passes through a plate, N^2 , adapted to slide sidewise in guides N^3 , secured to the top of the partition F^2 .

On the shaft O is secured the upwardly-extending crank-arm P , pivotally connected at its upper end with the bar P' , passing into the heater A near its top, and carrying at its inner 60 end a plate, P^2 , having an aperture, P^3 , adapted to register with the opening A^3 of the projection A^2 . The plate P^2 is supported and held in close contact with the projection A^2 by the guides P^4 , secured to the under side of the top 65 plate of the heater A .

On the shaft O is also secured the upwardly-extending arm Q , connected at its upper end

by the link Q' with the plate Q^3 , adapted to slide across the inner opening of the smoke-outlet flue A' , leading from the upper end of the 70 heater A to the outside after passing through the shell F .

On the shaft O is secured the downwardly-extending crank-arm R , connected by the link R' with the damper-door D , and on the shaft 75 O is also fastened the downwardly-extending crank-arm S , connected by the link S' with the lever S^2 , mounted to swing horizontally on the bearing S^3 , secured to the base F' of the casing F . The outer end of the lever S^2 is pivotally 80 connected with the circular band T , provided with a suitable number of plates, T' , adapted to slide on the upper edge of the ring F^8 , secured to the top of the base F' . One of the plates T' is provided with an aperture, T^2 , adapted 85 to register with the hot-air flue U , opening into the casing F and leading to the sides of the car, extending under the seats of the same, and the other plate, T' , registers with the cold-air-inlet flue U' , extending to the top of the car. 90

To the end of the arm I next to the guides I' is secured the rod V , which extends upward and passes through the partition F^4 and the top plate, F^5 . The part of the rod V extending above the top part, F^5 , is provided with rack-teeth V' , meshing into the pinion V^2 , secured to the wick-rod W' of the lamp W , preferably held on the outside of the top plate, F^5 . Lamps may also be placed on the roof of the car in the usual manner, and then the rod V is extended 100 to or connected in some suitable manner with the wick-rod W' , so that when the rod V is moved the wick-rod W' is turned in such a direction that the wick moves inward, thus extinguishing the light of the lamp. 105

The operation is as follows: When the car-heater is in the position shown in Figs. 2, 3, and 5, then the valve G^3 closes the outlet G^2 of the vessel G' , the latter being filled with a fire-extinguishing fluid introduced into the vessel 110 through the cup G^7 and the pipe G^6 . The valve G^9 remains closed. The valve G^3 is in a closed position, being held therein by the rod H , locked in its lowermost position by the bolt J engaging the top edge of the arm I , thus 115 holding the spring H^3 in a compressed condition. The bolt J locks the arm I on account of its connection with the lever K , which is weighted down at its long end by the ball L resting on the cup K^4 , the ball L being of such 120 a weight as to overbalance the spring K^6 , which is consequently compressed. The shaft O is held by the rod N in such a position that the apertures T^2 in the plates T' register with the pipes U , whereby the heat radiating from 125 the heater A passes into the car and along the same under the seats through said pipes U . The damper-door D is in such a position that its aperture D^2 registers with the aperture D^3 in the shell of the heater A , thereby admitting the air necessary for the combustion of the fuel on the grate-bars. The position of the shaft O and its crank-arms P and Q is such that the plate P^2 closes the aperture A^3 of the 130

projection A², while the plate Q² is removed from the opening of the smoke-flue A', and thus permits a free escape of the smoke arising from the burning fuel in the heater A. The latter is charged from the outside by the operator first opening the door F' of the casing F and then unlocking the main door C, so that the latter can be opened and fuel thrown into the fire-box of the heater, after which the door is again closed and locked by the lock C'. The door F' of the casing F is then closed again and locked by any suitable means. The grate-bars B can be shaken from the outside, whenever it is necessary, by moving the arm B⁴ forward and backward, so as to impart an oscillating motion to the shaft B³, which, by its pinion B² engaging the rack B', imparts a swinging motion to the grate-bars B. If the heater now receives a shock by a collision of the car in which it is located, or by any other accident, then the ball L is thrown from the cup K⁴ and rolls upon the partition F'. The lever K is thus relieved from the weight on its long end, so that the spring K⁶ forces the short end of the lever K downward and the long end upward. This motion imparts a swinging motion by means of the arm K' to the bell-crank lever J³, whereby the bolt J is withdrawn from the arm I, and the latter and the rod H are forced upward by the action of the compressed spring H³. This upward motion of the rod H unseats the valve G³, and the upward motion of the arm I imparts a swinging motion to the shaft O by means of the rod N and the crank-arm N'. The motion of the shaft O causes the crank-arm P to move the rod P' and its plate P² inward until the aperture P³ in the plate P² registers with the aperture A³ in the projection A², and as the valve G³ is unseated at about the same time, the fire extinguishing fluid in the vessel G now falls through the apertures A³ and P³ into the heater and upon the burning fuel, thus extinguishing the fire in the heater. At the same time the crank-arm Q moves the rod Q' inward, so that the plate Q² closes the smoke-flue A', and the motion of the shaft O causes the crank-arm R to move the damper-door D sidewise sufficiently so that the aperture D² will not register with aperture D³, thereby shutting off the draft. The crank-arm S, by its connection with the shaft O, imparts a swinging motion to the lever S', so that the circular band T causes the plates T' to slide until the apertures T² in said plates are moved entirely from the openings of the flues U and U', whereby the latter are closed by the plates T', and the heated air is prevented from passing into the car through the flues U, and the cold air is prevented from entering the casing F. The upward motion of the arm I causes the rod V to turn the wick-rod W', so that the light of the lamps is extinguished. It will be seen that as soon as the ball L is thrown, from whatever cause, from the cup K⁴, then the burning fuel in the heater and the lights in the car are extinguished, the escape of smoke from the heater is prevented,

the hot air generated in the heater is prevented from passing into the car through the flues U, and the draft necessary for combustion is shut off, thus making the device entirely fire-proof, as nothing can escape from the heater which might set fire to the car.

Having thus fully described my invention, I claim as new and desire to secure by Letters Patent—

1. In a car-heater, the combination, with a vessel containing a fire-extinguishing fluid and connected with the heater, of a valve closing the outlet of said vessel into the heater, a spring connected with said rod, an arm secured to said rod, a bolt for locking said arm in position, and a rod extending upward from said arm and connected with the wick-shafts of the lamps of the car, substantially as described. 80 85

2. In a car-heater, the combination, with a vessel containing a fire-extinguishing fluid and connected with the heater, of a valve closing the outlet of said vessel into the heater, a spring connected with said rod, an arm secured to said rod, a bolt for locking said arm in position, a rod extending upward from said arm and connected with the wick-shafts of the lamps of the car, and means, substantially as described, for unlocking said bolt, as set forth. 90 95

3. In a car-heater, the lever K, the spring K⁶, pressing against the short end of said lever, the ball L, supported loosely on the long end of said lever, and the bolt J, connected with said lever K, in combination with the arm I, held in a locked position by said bolt J as long as the ball L is supported by said lever K, the spring H³, pressing against said arm I, the rod N, connected with said arm I, the shaft O, connected by the crank-arm N' 100 105 with said rod N, the crank-arm Q, secured to said shaft O, and the plate Q², connected by the rod Q' with said crank-arm Q and adapted to close the smoke-flue of the heater, substantially as shown and described. 110

4. The combination, with the heater A, the casing F, surrounding the same, provided with suitable doors and having three horizontal partitions, F² F³ F⁴, forming three separate chambers above the top of the heater, of the vessel within the lowest chamber provided with an opening leading through the partition into the casing, a valve for said opening, a valve-rod extending up through the said vessel and middle partition, a spring on the valve-rod, the horizontal lever I, connected to the upper end of the valve-rod within the middle chamber, the locking-bolt engaging said lever, the lever K, connections between said lever and bolt, the spring for the short arm of the lever K, the rod K³, projecting from the long arm of said lever up through partition F⁴ into the top chamber and there provided with a cup, K⁴, and the ball within said cup, substantially as set forth. 115 120 125 130

5. The combination, with a car-heater, a surrounding casing forming a hot-air chamber and provided with inlet and outlet air-pipes having slides, a rock-shaft and levers connect-

ing the same with the damper and smoke outlet of the heater and with the slides in the air-pipes, of the vessel for containing the fire-extinguishing liquid communicating with the heater, a valve for said opening, a locking bolt and lever for said valve, and a weight releasing when displaced, the said bolt and lever, and a connection between said lever and the rock-shaft, whereby the contents of the vessel may be discharged into the heater, and the damper and smoke-outlet thereof and the hot and cold air pipes be simultaneously closed, substantially as set forth.

6. In a car-heater, the combination, with the casing F and the flues U, extending from said casing, of the apertured plates T', adapted to slide over the apertures of said flues U, the band T, connected with said plates T', the lever S², connected with said band T, the link S', connected with said lever S², the crank-arm S, connected with said link S', and the shaft O, adapted to receive a swinging motion, substantially as shown and described.

7. The car-heater A, the casing F, inclosing said car-heater A, the flues U, leading from said casing F, the fire-extinguishing device G, connected with said heater A, and the smoke-outlet flue A', connected with said heater A, in combination with the ball L, the lever K, supporting said ball L loosely on its long end, the spring K⁶, pressing against the short end of said lever, the bolt J, connected with said lever K, the arm I, held in a locked position by said bolt J, the spring H³, pressing against said arm I, and means, substantially as described, for closing the flues U and A' and opening the fire-extinguishing device G, so that the fluid in said device passes into the interior of the car-heater, substantially as shown and described.

8. The combination, with the car-heater A, of the casing F, the partitions F², F³, and F⁴ in said casing, above the top of the heater, the base F', formed on said casing, and the cover F⁵, secured to said casing, substantially as shown and described.

9. The combination, with the car-heater A, provided with the perforated projection A², of

the vessel G', connected by its outlet G² with said projection A², the valve G³, seated on said outlet, the filling-pipe G⁶, connected with the interior of said vessel G', the valve G⁹ in said pipe G⁸, and the rod G¹⁰ for operating said valve G⁹, substantially as shown and described. 55

10. In a car-heater, the lever K, the rod K³, secured to one end of said lever K, the cup K⁴, held on the upper end of said rod K³, the ball L, held loosely on said cup K⁴, and the spring K⁶, pressing against the other end of said lever K, in combination with the vessel for the extinguishing material, communicating with the heater and provided with a valve having a lever connected therewith, the bell-crank lever J³, connected by the arm K' with said lever K, and the bolt J, pivotally connected with said bell-crank lever J³, engaging the valve-lever, whereby when said ball L is removed from said cup K⁴ then said bolt J is withdrawn, substantially as shown and described. 65 70

11. In a car-heater, the combination, with the vessel G', having the outlet G² of the valve G³, adapted to be seated on said outlet G², the stem G⁴, having a slot G⁵, and projecting upward from said valve G³, the rod H, 75 partly hollow at its lower end into which fits said stem G⁴, the pin H', secured to said rod H and passing through said slot G⁵, and the spring H³, pressing against said stem G⁴, thus making said valve G³ yielding on said rod H, 80 substantially as shown and described.

12. In a car-heater, the vessel G', filled with a fire-extinguishing fluid, and the yielding valve G³, held on the outlet-pipe G² of said vessel, in combination with the car-heater A, 85 having the apertured projection A², connected with said outlet of the vessel G', the apertured slide P², held below said projection A² and secured to the rod P', and the crank-arm P, secured to the oscillating shaft O, substantially as shown and described. 90
